UNITED STATES PATENT OFFICE.

LOUIS H. GEBHART, OF DAYTON, OHIO, ASSIGNOR TO THE GEBHART FOLDING BOX COMPANY, OF DAYTON, OHIO, A CORPORATION OF OHIO.

DESIGN FOR A BOX BLANK OR SIMILAR ARTICLE.

Application filed May 17, 1928. Serial No. 26,710. Term of patent 14 years.

To all whom it may concern:

Be it known that I, LOUIS H. GEBHART, a citizen of the United States, residing at Dayton, in the county of Montgomery and State of Ohio, have invented a new, original, and ornamental Design for a Box Blank or Similar Article, of which the following is a specification, reference being had to the accompanying drawing, forming a part thereof.

The accompanying drawing is a plan view of a box blank or similar article embodying my new design.

I claim:

The ornamental design for a box blank or similar article, as shown.

LOUIS H. GEBHART.
